UNITED STATES PATENT OFFICE.

BRUNO STANISLAUS HERRMANN, OF CHICAGO, ILLINOIS, ASSIGNOR OF ONE-HALF TO VINCENT HARTER, OF SAME PLACE.

BREECH-LOADING FIRE-ARM.

SPECIFICATION forming part of Letters Patent No. 415,509, dated November 19, 1889.

Application filed May 7, 1889. Serial No. 309,953. (No model.)

To all whom it may concern:

Be it known that I, BRUNO STANISLAUS HERRMANN, a subject of the Emperor of Germany, residing at Chicago, in the county of Cook and State of Illinois, have invented certain new and useful Improvements in Magazine-Guns, of which the following is a specification, reference being had therein to the accompanying drawings.

10 This invention relates to magazine fire-arms of the class in which the breech of the barrel is closed by a bolt sliding in line with the axis of the barrel and operated by a lever from below, the movement of said lever with-
15 drawing the spent cartridge, cocking the hammer, recharging the gun, and relocking the breech mechanism; and it consists, principally, in the construction and arrangement of the breech-locking bolt, in combination with the
20 breech-chamber piece of the gun and with the bolt-operating lever, the object being to produce a more simple, perfect, and safe locking device, all as will be hereinafter more fully described and specifically claimed.
25 In the accompanying drawings, Figure 1 represents a longitudinal vertical section of the gun with the parts in position as immediately after shooting, and Fig. 2 is a sectional elevation showing the breech-bolt with-
30 drawn and ready for reloading. Fig. 3 is a top view of the gun with the parts in same position as in Fig. 1. Fig. 4 is a transverse sectional view of the breech-bolt and the bifurcated end of the bolt-operating lever. Fig.
35 5 is a section on line 5 5 in Fig. 1. Fig. 6 is a side elevation, and Fig. 7 a bottom view, of the breech-bolt detached, its parts being shown in relative position after locking said breech-bolt ready for firing; and Fig. 8 is a
40 bottom view of the breech-bolt, its parts being in relative position as when withdrawn from the breech of the barrel for reloading the gun.

Corresponding referential characters in the several figures of the drawings designate like parts.

A denotes the breech end of the barrel, and B the magazine-tube, arranged below said barrel to be parallel therewith.

50 C is the breech-mechanism chamber, and D the gunstock.

The breech-locking bolt consists of three pieces, E, F, and G, all cylindrical and of equal exterior diameter, to be guided in the cylindrically-bored upper portion of chamber 55 C to move in line with the axis of barrel A. The piece E of the bolt has a rearward cylindrical projection 1, of smaller diameter, and the piece G of the bolt has a forward projection 2, also of a smaller diameter, and upon 60 these projections 1 and 2 is sleeved the tubular piece F, so as to slide and turn loosely thereon, and the pieces E and G are bored through their axes for the firing-pin H, extending the entire length of the bolt E F G, 65 with its forward end reduced in diameter to provide a shoulder, and with a spiral spring 3 interposed between said shoulder and a shoulder in the bore of piece E for pushing said pin H rearward. This pin H is held in the 70 bolt by a screw 4, tapped through the top of bolt-piece G, with its point entering a groove sunk into pin H to allow a sufficient longitudinal sliding movement therein. The piece E of the bolt has a longitudinal rib or feather 75 6, the piece F a rib or feather 7, and the piece G a rib or feather 8, all three ribs or feathers 6, 7, and 8 projecting into a longitudinally-slotted opening 9 in the top of the breech-chamber piece C, and in its forward 80 end this slot 9 is widened toward the right-hand side, providing a shoulder 10 and an opening large enough for inserting a cartridge. By moving the bolt forward until the piece E has closed the breech end of the barrel A a 85 partial revolution of piece F will bring the feather 7 to bear against shoulder 10, and will thus securely lock the bolt in this position. The feather 6 of the piece E of the breech-bolt is grooved longitudinally for a spring 11, 90 having a forwardly-projecting hook 12, which will grasp the rear flange of the cartridge, and the rearwardly-extended end of this spring 11 has a downwardly-projecting lug 13, engaging a segmental groove 14 of piece F 95 of the bolt for coupling the pieces E and F, at the same time allowing a rotating movement of piece F. Piece E of the bolt is also longitudinally grooved in its bottom side for a spring 15, being diametrically opposite to spring 11. This spring 15 has a head projecting beyond the forward end of piece E, and

being chamfered. When pushing the cartridge into the gun-barrel, the chamfered face of the head of spring 15 will be pushed downward by the flange of the cartridge, while the hook 12 of spring 11 will grasp the flange of the cartridge, and after firing, by retracting the bolt, said hook 12 will extract the cartridge-shell, which, as soon as its end clears the breech of the gun-barrel, will be thrown upward by the force of spring 15, its chamfered head, to release itself, pushing the lower flange of the cartridge-shell forward, and thereby the forward end of the cartridge-shell upward, to be thrown out through the widened portion of slot 9 of the breech-chamber piece C. The piece F, sleeved upon the forward projection 2 of piece G of the bolt, is slotted longitudinally from the rear forward a short distance, then laterally a short distance, which slot 16 is then extended forwardly on a spiral line, and the head of a screw 17, tapped into piece G of the bolt, engages this spiral slot 16 in a manner that a telescopic movement of the pieces F and G will impart a rotating movement to piece F. While the bolt is in its retracted position for reloading the gun the parts E, F, and G are in the relative positions shown by Figs. 2 and 8, when the feathers 6, 7, and 8 are in line with each other and in the narrow portion of slot 9 in the top of the breech-chamber piece C, which will prevent either piece E, F, or G from rotating, thus holding them in line while the bolt is being pushed forward until piece E of the bolt is in close contact with the breech end of barrel A, where the projecting end of springs 11 and 15 will enter notches provided for their reception, and whereby at the same time the rear end of feather 7 is brought in line laterally with shoulder 10 of the slotted opening of breech-chamber piece C, when a further forward movement of piece G, by the engagement of its screw-head 17 with the spiral slot 16 of piece F, will rotate said piece F, thereby turning the feather 7 to bear against shoulder 9 and locking the bolt firmly in its assumed position. When retracting the bolt, the longitudinal movement of piece G, to which the power is applied, will first rotate the piece F again to move the feather 7 clear of the shoulder 10 and into line with feather 8 before the pieces E and F will move with it longitudinally, the spiral slot 16 in either case bringing about such rotating movement.

55 The bolt is operated by a lever L, pivoted in the lower part of the breech-chamber piece C on a pin 18, and having a bifurcated upward end 19, grasping the notched or recessed sides of bolt-piece G. The downward-projecting end of this lever is conveniently curved and shaped to provide a handle, which, when turned against the stock of the gun, will at the same time form the trigger-guard. When swinging the handle of this lever L rearward, the bolt is moved forward, and vice versa. The hammer M is pivoted into the rear portion of the receiver C on a pin 20, the hub of

this hammer at the same time forming the tumbler, provided with shoulder for the trigger N to engage and hold the hammer M cocked. 70 The hub or tumbler part of this hammer M is also connected by a link with the end of a leaf-spring O, that swings the hammer when released by pulling the trigger N. When retracting the bolt E F G for reloading the gun 75 by swinging the lever L, the hammer M at the same time is being pushed back by such bolt, and is swung to its cocked position, as shown by Fig. 2, in which position it will remain while the bolt is being moved forward again 80 for closing the breech of the barrel, and then by pulling the trigger the hammer M will strike the rearwardly-projecting end of the firing-pin H for exploding the cartridge, as shown by Fig. 1. 85

The cartridge-carrier P, provided to receive a cartridge from the magazine-tube B by the expansion of a spiral spring in such tube B, and to elevate the same into position for the end of bolt-piece E to push it forward into 90 the barrel A, and then to be locked behind it, consists of an arm P, pivoted in breech-chamber piece C on a pin 21. This arm P is concaved for holding the cartridge with a shoulder 22, against which the rear end of the cartridge 95 will abut, while when elevated the end of the arm will provide a butt-end against the next following cartridge to be retained in tube B until said arm is dropped to its lower position again. Directly over the pin 21 the arm P 100 has a cam projection 23, engaging at the end of the forward movement of the bolt with a tooth 24 of piece G for tilting the arm P to its lower position, and at the end of a rearward movement of the bolt with a tooth 25 of piece E for swinging the arm P to its upper position, a leaf-spring Q bearing against either one of two flat faces of lever P, below pin 21, for holding said arm in either one of the two positions. 110

When this gun is used as a repeater, the motion of the lever L extracts the spent shell of the previous charge, cocks the hammer, recharges the gun, and relocks the breech-bolt, while when used as a single-loader the cartridge is inserted through the widened front portion of slot 9 in the breech-chamber piece, through which also the spent cartridges are removed. 115

What I claim is— 120

1. In a magazine fire-arm, the breech-closing bolt guided in the receiver to move longitudinally in line with the axis of the barrel, said breech-bolt consisting of pieces E, F, and G, all loosely connected, and the pieces E and 125 F telescoping with each other and coupled by a screw or stud rigid with one piece and engaging a spiral groove of the other piece, and a rib or feather integral with piece F and in juxtaposition with such rib or feather while 130 the bolt is closed against the breech of the barrel, and a shoulder 10 in the receiver, all in a manner that a forward movement of piece G of the bolt will impart a rotating move-

ment to piece F and to the rib or feather thereof to turn behind shoulder 10 for locking the bolt after closing the breech of the barrel, substantially as set forth.

- 5 2. In a magazine fire-arm, the breech-closing bolt consisting of pieces E, F, and G, all loosely connected, and the middle piece F sleeved upon the rear piece G and coupled therewith by a screw or stud rigidly secured 10 to piece G and engaging spiral groove 16 of piece F, whereby a telescoping movement will impart a rotating movement to piece F, and each section E, F, and G provided with a rib or feather, in combination with the receiver 15 providing a guide for the breech-bolt and for the ribs or feathers thereof, and a shoulder 10 in juxtaposition for the feather of the middle piece F to turn against with the rotation of such piece for locking the bolt automatically after closing the breech of the barrel, all 20 substantially as set forth.
3. In a magazine fire-arm, the breech-bolt composed of pieces E, F, and G, the pieces E and F being loosely connected and the piece 25 F being sleeved upon the forward end of piece G, providing a telescopic movement and hav-

ing a spiral slot 16, engaging a screw-head 17 of piece G, and the several pieces having longitudinal ribs or feathers moving in a slot 9 of the receiver, also provided with a shoulder 30 10 for the feather 7 to be turned against by the forward movement applied to piece G by means of a bifurcated lever L, engaging the recessed bearings of said piece G, that the closing of the breech of the barrel by the bolt 35 will automatically lock such bolt, substantially as set forth.

4. In a magazine fire-arm of the class described, the cartridge-carrying arm P, swinging on pin 21, having cam projection 23, engaging the teeth 24 and 25 of the longitudinally-guided breech-bolt, and having two flat faces angular to each other below the pivot-pin as a bearing for the end of a leaf-spring Q, substantially as and for the purpose set forth.

In testimony whereof I affix my signature in presence of two witnesses.

B. STANISLAUS HERRMANN.
